UNITED STATES PATENT OFFICE.

ALBERT DAVIS SMITH, OF LANCASTER, PENNSYLVANIA.

POST-HOLE DIGGER.

SPECIFICATION forming part of Letters Patent No. 752,115, dated February 16, 1904.

Application filed November 27, 1903. Serial No. 182,824. (No model.)

To all whom it may concern:

Be it known that I, ALBERT DAVIS SMITH, a citizen of the United States, residing at Lancaster, in the county of Lancaster and State 5 of Pennsylvania, have invented certain new and useful Improvements in Post-Hole Diggers; and I do hereby declare the following to be a full, clear, and exact description of the invention, such as will enable others skilled in 10 the art to which it appertains to make and use the same.

This invention relates to post-hole diggers of the double-shovel pivoted-jaw kind; and it consists in the construction and combination 15 of parts hereinafter more particularly set forth and claimed.

Figure 1 represents a perspective view of my improved double shovel and tamper, especially adapted to each other and collectively 20 constituting my post - hole digger. Fig. 2 represents a cross-section of the same, taken just above the shoulders. Fig. 3 represents a side elevation of the two members of the double shovel detached. Fig. 4 represents a 25 side elevation of the shovels closed, and Fig. 5 represents a similar view of the double shovel in position for separating its members.

A and A' designate, respectively, the two shovel-blades or shovel-shaped digging-jaws, 30 having L-shaped plates B B' rising centrally therefrom and rigid therewith. These plates have laterally-extending feet b b' on each side of them, resting on the horizontal and segment-shaped tops a a' of the said shovels and riveted 35 or otherwise secured thereto. The broad and long horizontal arms b² b³ of these plates overlap, and plate B is provided on its face with a horizontal or slightly-oblique button C, having a thin elongated head, while plate B' has a key-hole-slot D, consisting of a circular central part d to receive the cylindrical stem c of said button and two opposite radial parts d', normally in alinement at an angle of about forty-five degrees. The said slot permits the said 45 head to pass through it when the said plates are so placed as to bring these parts exactly opposite each other. The length of stem c and the thickness of B' exactly correspond, so that the said stem constitutes a pivot for the 50 said jaws, and the said head fits just in front

of the plate B', not impeding the pivotal movement of either plate, but effectually locking the two plates and their jaws together after said jaws have been turned into their normal position for use. (Illustrated in Fig. 1.)

At the upper and outer corners of the L-shaped plates B B' and on opposite sides thereof blocks or shoulders E F are located, having square tops to receive the stroke of the tamper. Long handle-rods G H rise from 60 the said plates and are rigid therewith, the rod G being on the same face of the plate B as is block or shoulder E, but at the edge of the said plate on the other side of the pivoted point, and the rod H being similarly arranged 65 on plate B' with respect to block or shoulder F. Each of these rods is bent outward at the upper end to a handle or hand-grasp g or h. The said rods are thus diametrically opposite each other, and the said blocks or shoulders are also diametrically opposite each other. A line connecting the rods will cross a line connecting the blocks over the middle of the pivot and the central vertical line of the tool. The shoulders are raised slightly above 70 the level of the tops of the shovel-blades.

I designates a tamping-tool consisting of a long bar, having at its lower end a plate or casting J of sufficient length to extend from block or shoulder E to block or shoulder F, 80 when these are at their greatest distance apart. This plate, at opposite sides of its ends, is provided with flat integral horns j j', overlapping the said blocks and giving to the plate as a whole approximately an S form, especially as 85 the inner edges of these horns are curved at their junction to the body of the plate to fit the said rods, as shown in Figs. 1 and 2. A wooden facing K for said plate is the part which actually strikes the shoulders. The nature of its material deadens the sound of the stroke and lessens the wear on the shoulders or blocks E F.

The operation of my post-hole digger is as follows: The shovels and tamper being in the 95 position shown in Fig. 1, the latter is raised and brought down on the shoulders E F, being guided by the rods G H and horns j of plate J, so as to insure vertical motion and certainty of stroke. The weight of the bar 100

and plate constituting the tamper is sufficient to make the stroke effective; but it may of course be repeated as often as necessary until the shovels have been driven into the soil to the required depth. The handles are then moved toward each other, closing the jaws into the position shown in Fig. 4, after which they are lifted, opened to dump out the earth, and returned to the post-hole, taking the position shown in Fig. 1 in readiness for repeated service.

If desired, the two plates and attached parts may be separated by reversing the procedure of attachment above described. Each shovel 15 may then be used as such. The tamper has a spade-blade L formed on the upper end of its bar and may be used independently as the latter tool when reversed; but of course the chief utility of the digger will be found in its use, 20 as above described, with the three members in coöperation.

The shovel-blades A A' of course need not have precisely the shovel form, though this is preferred. When separated, the digger's foot 25 may press either on the shoulder or on the closed top of the shovel. For use in the normal way, above described, as a hole-digger there is an advantage in raising the shoulders above the digging-jaws or shovel-blades and interposing the plates B B', as the jar of the heavy 30 tamper on the shovel-blades and the consequent risk of injury to them will be less.

Of course the device, though primarily a post-hole digger, may be used for any purposes of excavation to which it is applicable.

Having thus described my invention, what I claim as new, and desire to secure by Letters Patent, is—

1. In a digging device, a pair of digging-jaws, pivoted together and provided with handle-rods as well as with shoulders, in combination with a tamper, arranged to strike on the said shoulders and having parts which engage the said rods, to be guided thereby in their up-and-down movement, substantially as set forth.

2. In a digging device, a pair of shovels, pivoted together and provided with handle-rods as well as with shoulders, in combination with a tamper, arranged to strike on the said shoulders and having a plate J provided with horns j, which overlap the said shoulders and also fit against the said rods to be guided thereby, substantially as set forth.

3. In a digging device, a pair of shovels, connected together by parts having, respectively, a button and a slot, the said button having a cylindrical stem to serve as a pivot and

a broader head for preventing the detachment of the shovels while in operative position, and 60 the said slot consisting of a central opening, fitting said stem, and two opposite radial parts fitting said head, the slot and button-head being also arranged at different angles, substantially as set forth. 65

4. In a digging device, a pair of shovels, having a pair of plates rigid with them, respectively, said plates being detachably pivoted together and provided with a pair of shoulders, raised above the tops of the digging-jaws or shovel-blades, substantially as set forth. 70

5. In a digging device, a pair of shovels, provided with a pair of raised L-shaped plates, which are pivoted together, the said plates being provided with a pair of shoulders on their tops and with a pair of handle-arms, the said arms being diametrically opposite to each other and the said shoulders being diametrically opposite each other, substantially as set 80 forth. 75

6. In a digging device, a pair of shovels, provided with a pair of raised L-shaped plates, which are pivoted together, and provided with diametrically opposite handle-rods and diametrically opposite shoulders, in combination with a tamper having vertical, independent motion and provided with a tamping-plate which has horns overlapping the said shoulders and fitting the said rods to be guided thereby, substantially as set forth. 90

7. In a digging device, a pair of shovels, provided with handle-rods, also with shoulders raised above the shovel-blades and connected thereto by intervening parts, in combination with a tamper, provided with a tamping-plate, which overlaps said shoulders, fits said rods, to be guided thereby, and has on its under side a facing of wood, substantially as and for the purpose set forth. 95 100

8. In a digging device, a pair of shovels provided with overlapping raised plates, having handle-rods rigid therewith and shoulders formed on their tops, in combination with a tamper, adapted to strike said shoulders as it descends, and provided with parts which fit and guide the said rods, substantially as set forth. 105

In testimony whereof I have signed my name to this specification in the presence of two sub- 110 scribing witnesses.

ALBERT DAVIS SMITH.
